COMBINED SEWING MACHINE AND SUPPORTING TABLE

Henry R. Kaiser, Morton Grove, Ill., assignor to Union
Special Machine Company, Chicago, Ill., a corporation
of Illinois

Filed Feb. 16, 1968, Ser. No. 10,617

Term of patent 14 years

Int. Cl. D15—08

U.S. Cl. D70—1

FIG. 1

FIG. 2

FIGURE 1 is a front perspective view of a combined sewing machine and supporting table showing my new design;

FIGURE 2 is a rear perspective view thereof;

FIGURE 3 is a left end view thereof;

FIGURE 4 is a front elevational view thereof;

FIGURE 5 is a top plan view thereof shown broken away for convenience of illustration; and

FIGURE 6 is a right end view thereof.

I claim:

The ornamental design for a combined sewing machine and supporting table, as shown and described.
